(57) **CLAIM**

The ornamental design for a biodiffusion chamber, as shown and described.

DESCRIPTION

FIG. 1 is a top perspective view of a first embodiment of the biodiffusion chamber;
FIG. 2 is a bottom perspective view thereof;
FIG. 3 is a front view thereof;
FIG. 4 is a back view thereof;
FIG. 5 is a left side view thereof;
FIG. 6 is a right side view thereof;
FIG. 7 is a top view thereof; and
FIG. 8 is a cross section view thereof from front to back.
FIG. 9 is a top perspective view of a second embodiment of the biodiffusion chamber;
FIG. 10 is a bottom perspective view thereof;
FIG. 11 is a front view thereof;
FIG. 12 is a back view thereof;
FIG. 13 is a left side view thereof;
FIG. 14 is a right side view thereof;
FIG. 15 is a top view thereof; and
FIG. 16 is a cross section view thereof from front to back.
FIG. 17 is a top perspective view of a third embodiment of the biodiffusion chamber;
FIG. 18 is a bottom perspective view thereof;
FIG. 19 is a front view thereof;
FIG. 20 is a back view thereof;
FIG. 21 is a left side view thereof;
FIG. 22 is a right side view thereof;
FIG. 23 is a top view thereof; and
FIG. 24 is a cross section view thereof from front to back.
FIG. 25 is a top perspective view of a fourth embodiment of the biodiffusion chamber;
FIG. 26 is a bottom perspective view thereof;
FIG. 27 is a front view thereof;
FIG. 28 is a back view thereof;
FIG. 29 is a left side view thereof;
FIG. 30 is a right side view thereof;
FIG. 31 is a top view thereof; and
FIG. 32 is a cross section view thereof from front to back.
FIG. 33 is a top perspective view of a fifth embodiment of the biodiffusion chamber;
FIG. 34 is a bottom perspective view thereof;
FIG. 35 is a front view thereof;
FIG. 36 is a back view thereof;
FIG. 37 is a left side view thereof;
(Continued)

FIG. 38 is a right side view thereof;
FIG. 39 is a top view thereof; and,
FIG. 40 is a cross section view thereof from front to back.
The broken lines immediately adjacent the shaded areas represent the bounds of the claimed design while all other broken lines are directed to environment and are for illustrative purposes only; the broken lines form no part of the claimed design.
